UNITED STATES PATENT OFFICE

2,636,258

FLUID CAN PUNCH AND OPENER

Allen Jones, Darby, Mont.

Application February 23, 1949, Serial No. 77,783

1 Claim. (Cl. 30—6.1)

1

This invention relates to punching and opening devices for fluid-containing cans, and particularly to a manually-operated fluid can punch and opener.

The main object of my invention is to provide mechanical means for instantly and conveniently opening cans containing beverages, fruit and vegetable juices, paints, varnishes, oils and the like, by perforating the top of the can involved in two spaced positions, allowing the fluid contents to be poured from the can thus opened.

Another object is to provide a manually-operated mechanical punching device adapted to support a can to be opened in a predetermined position for ensuring reception of the punching instrumentalities of the device invariably in proper position to cause satisfactory pouring and emptying of the can punched by the device.

A further object is to have a vertically-guided punch assembly with a handle forming a lever connected to the punch assembly by means of a link allowing free movement of the lever while efficiently transferring the pressure produced thereby to the punch assembly.

It is also an object to have upon a device of this character resilient means for returning the punch assembly and handle to initial position when the handle has been depressed to punch the top of a can.

A practical object is to have the punch assembly of such a device so arranged that aside from the pointed punch member producing the ventilating opening in the can, the cutting punch member producing the pouring opening therein is disposed in such position as to present the acute end of the opening to the edge of the can in order to facilitate control of the pouring or drinking from the can when punched.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a front elevation of a fluid can punch and opener made according to the invention and embodying the salient features thereof in a practical form;

Figure 2 is a side elevation of the same can-opening and punching device as shown in Figure 1;

Figure 3 is a transverse section taken on line 3—3 in Figure 1;

2

Figure 4 is another transverse section taken on line 4—4 in Figure 1.

In the various views, the same reference numerals indicate the same or like parts.

Can openers and punches are, of course, well known as operated by hand, but due to the fact that one hand is occupied either in holding the can to be opened or retaining it steady on a support while the other hand is used to hold the can opener or punch, a certain amount of time, as well as manual strain, is involved in opening a can in order to drink or pour the fluid from the can. In order to obtain a proper action of the fluid when being poured from a can, it is, of course, necessary to have not only a pouring opening in the top of the can, but also a ventilation opening to allow air to enter and displace the fluid issuing from the pouring opening. As already intimated, hand punches which will effect this result are naturally limited in their operation, which is necessarily slow, while in restaurants or in other establishments dispensing fruit juices, beverages and the like from cans to patrons, expedition is required in opening the cans which obviously necessitates the use of mechanical means merely controlled or operated by the hand.

Upon considering this problem, it has occurred to me that a mechanical device should be available which automatically holds the can in proper position so that no attention need be directed to the holding of the can in proper position, while on the other hand, the device should also be equipped with facilities for punching the two required holes simultaneously in the top of the can to be emptied. As a result, I have succeeded in producing a device of the outlined character, as will now be more fully described.

Hence, in the practice of my invention, and referring again to the drawing, a fluid can punch and opening device, generally indicated at 5, primarily includes a rear supporting plate 6 intended to be secured to a wall or to the side of a bar or counter by means of screws in holes 7, 7, etc., to the forward surface of which near the lower end is brazed or welded a horizontal shelf 8 reinforced by a central supporting web 9 beneath the same and welded or brazed to the same back plate 6, while at the side edges 10 and 11 of shelf 8 a pair of stops 12, 13 are brazed or welded into position in order to limit a can indicated in broken lines at 14 from shifting laterally on shelf 8. Members 12 and 13 may be short pieces of metal, such as round or square rods, or bars, or the like, while the back plate 6 and shelf 8 are

preferably heavy sheet metal, such as sheet iron or sheet steel.

Spaced short distances from the upper end of back plate 6 are a pair of forwardly-extending horizontal bracket members 15 and 16 welded or brazed to the back plate and having a vertical tubular guide 17 extending rigidly through both members, being preferably brazed or welded thereto, in substantial parallelism to the back plate 6. A vertically-slidable plunger 18 extends downwardly through tubular guide 17 and to the lower end of this plunger is fixed a punch assembly plate 19 by means of a screw 20. The mentioned punch assembly plate 19 is elongated and at one end 21 has the lower end 22 of a tension coil spring 23 engaging in a hole 27 therein, the upper end of this spring at 24 engaging about the outer end of a horizontal stud 25 extending rigidly forward from the back plate 6 to which it is brazed or welded. Adjacent to the rear end 21 of punch assembly plate 19 is fixed a depending pointed stud or punch member 26. The lower end or coil 22 of spring 23 may be arranged to encircle the upper end of punch 26 immediately beneath the punch plate 19 instead of engaging in hole 27 in the punch plate, if so desired, but independent engagement with the punch plate through the hole mentioned is preferable. At the other end of horizontal punch plate 19 on the other side of screw 20 is a downwardly-extending triangular cutter 28 disposed at an angle of substantially 45° and cut at the sides to form the triangular cutter 28, having the lower pointed extremity 29 thereof preferably sharpened and pointed directly down, but terminating slightly above the level of the lower pointed end 30 of punch 28. Due to the extension of plate 19 beneath the lower end of tubular guide 17 toward end 21, the plate also forms a stop engaging against the mentioned lower end of the tubular guide, thus limiting the upward movement of plunger 18. Normally, the spring 23 tends to raise the plunger into the position in which plate 19 would tend to abut the lower end of tubular guide 17, but allow the plunger to be depressed downwardly in order to bring the punches 26 and 28 into contact with the top indicated at 31 in broken lines of can 14, as will now be more specifically considered.

Upon the upper end of back plate 6 are fixed a pair of upright parallel plates 32, 33 which are welded or brazed to the back plate and extend down to and are similarly brazed or welded to the upper bracket member 15, the two plates 32 and 33 being spaced apart a sufficient distance to receive the lower flat end 34 of a lever 35 between them, this lever throughout the greater portion of its upper length being preferably rounded to form the handle 36. The flattened portion of lever 35 extends upwardly a short distance to a lower intermediate point noted at 37, the lever being flattened on both sides to provide flat engaging faces slidably guided between the plates 32 and 33 between which the lower end 34 is connected for rocking movement about a horizontal axis as by pivot bolt 38 extending through both plates and the mentioned lower end of the lever. The upper end of plunger 18 is flattened at 39, and is substantially of the same transverse dimensions as the flattened portion 40 of lever 35. To the mentioned flattened upper end 39 of the plunger is connected for pivotal movement about a horizontal axis, a pair of similar links 41, 42 as by means of a further pivot bolt 43, while the upper ends of these links are connected for

pivotal movement about a horizontal axis to the flattened portion 40 of lever 35 as by means of a third pivot bolt 44, and both links in upper idle position engaging against a forward upwardly-inclined portion 45 on each plate 32 and 33 to cooperate with the plunger 18 and its punch assembly plate 19 below the lower end of tubular guide member 17 to form the stop means determining the upper position of the plunger and handle 36, as well as the punches 26 and 28.

The arrangement is such that when the can 14 is placed between the two side stops 12 and 13 on supporting shelf 8, the top 31 of the can will be disposed a short distance below the lower ends 29 and 30 of the punching implements depending from plate 19 preparatory to punching two different holes in the can. Preferably, the back plate 6 is provided with a transverse stop 46 upon the front face thereof and spaced an exact distance from the bottom shelf 8 to accommodate the height of the can, and thus contribute to the stability of the latter when standing on shelf 8. When the can is thus placed in position, lowering handle 36 will cause links 41 and 42 to lower plunger 18 through tubular guide member 17 and thereby the plate 19 with its punch 26 and cutter 28 to cause both the lower end 30 of punch 26 and the lower pointed portion 29 of cutter 28 to enter the top 31 of the can. The handle 36 being lowered sufficiently to cause the punch and the cutter to enlarge the holes to the predetermined sizes, release of the handle will allow spring 23 to draw punch assembly plate 19 upward with plunger 18, links 41 and 42 and handle 36, simultaneously withdrawing punch 26 and cutter 28 from the can. The result is that the operating parts are all restored to initial positions ready for punching another can as soon as the punched can is replaced. As indicated in broken lines at 47, the round hole produced by punch 26 which could, of course, be of any other form, merely serves as a ventilation opening to allow entry of air into the can to displace the fluid flowing from the can through the other opening, indicated in broken lines at 48, which is produced by cutter 28. By causing the narrow pointed end 49 of pouring opening 48 to be directed toward the edge of the can, a well-controlled regulation of the pouring is possible, and thus forms an advantageous feature of the operation of the invention and the arrangement of the cutter.

Manifestly, variations may be resorted to and parts and features may be modified or used without others within the scope of the appended claim.

Having now fully described my invention, I claim:

A fluid can-opening and punching device including a substantially upright supporting member forming a back plate, a horizontally-extending supporting shelf projecting rigidly forward from the lower end of the back plate, a pair of stops fixed at the sides of the supporting shelf for locating a can thereon in predetermined position, a further stop fixed on said back plate above said supporting shelf to hold the can down upon the latter, a pair of forwardly-extending bracket members fixed upon the back plate adjacent to the upper end thereof, a vertically-disposed tubular guide member extending rigidly through both bracket members, a vertically-movable plunger slidably mounted in said tubular guide member, a pair of upwardly-extending and substantially parallel plates fixed upon the upper

end of said back plate in spaced-apart relation, a manually-operated lever pivotally connected at the lower end thereof to both upwardly-extending plates and extending between the latter, a link pivotally connected at one end thereof to an intermediate portion of said lever and at the lower end thereof to the upper end of said plunger, a spring-supporting member rigidly projecting from the upper end of said back plate, a substantially horizontal elongated punch assembly plate fixed to the lower end of the plunger, a depending punch fixed upon the punch assembly plate adjacent to one end thereof, a tension spring connected to the same end of said punch assembly plate and to said spring-supporting member on the back plate, a downwardly-inclined triangular cutter formed upon

the other end of the punch assembly plate in spaced relation with respect to the punch and with the cutting point of the cutter in maximum remote position from the latter.

ALLEN JONES.
